UNITED STATES PATENT OFFICE.

WILLIAM SCHWAGERMANN, OF YONKERS, NEW YORK, ASSIGNOR TO WARD LEONARD ELECTRIC COMPANY, A CORPORATION OF NEW YORK.

ELECTRIC CONTROLLING MEANS.

1,362,898.

Specification of Letters Patent. Patented Dec. 21, 1920.

Application filed April 25, 1916. Serial No. 93,357.

To all whom it may concern:

Be it known that I, WILLIAM SCHWAGERMANN, a citizen of the United States, residing at Yonkers, in the county of Westchester and State of New York, have invented certain new and useful Improvements in Electric Controlling Means, of which the following is a full, clear, and exact specification.

The principal object of my invention is to provide a new and improved device for controlling or regulating a storage battery system. Another object of my invention is to provide a regulator for an electric system such as is employed on motor cars for lighting, ignition, starting and other purposes. Still another object of my invention is to provide a regulator with means to prevent accidental discharging of the storage battery. These and other objects will be made apparent in connection with the following specification and claims, taken with the accompanying drawings, in which I have illustrated one specific embodiment of my invention. It will be understood that the invention itself is defined in the appended claims.

Referring to the drawings, Figure 1 is a semi-diagrammatic view of the device;

Fig. 2 is a diagram showing the circuits more fully than in Fig. 1;

Fig. 3 is a face view of a vibratory contact;

Fig. 4 is a back view of another contact, and

Fig. 5 is a diagram of a detail.

A direct current shunt wound generator with armature 2 and field windings 3 is driven by an automobile engine 1. From the brushes of this generator, conductors lead to charge the storage battery 4.

A controlling magnet with the iron core 6 and iron pole pieces 7, 7' is provided with two windings, a shunt winding 8 and a series winding 9. At the respective ends of the magnet are two armatures supported from the pole pieces at the opposite ends. Thus the pole piece 7 has a rigid attachment 10 carrying a flexible strip 11 of phosphor bronze, which supports the armature 12 in proximity to the pole piece 7'. This armature 12 has a flat spring finger 14 carrying a contact 15 adapted to engage the fixed contact 17. The leaf spring 18 tends to hold the armature 12 away from the pole piece 7' and it may be adjusted through the screw 20 supported by the frame extension 19.

Another armature 22 is positioned oppositely to the one heretofore described. This has a flexible support 23 mounted at 24 on the pole piece 7' and the armature 22 extends in proximity to the pole piece 7. It carries a spring finger with two contacts 25 and 26 respectively adapted to engage the fixed contacts 30 and 31. These contacts are normally held closed by the spring 18', which may be adjusted through the screw 20'.

On the core 6 are two coils, a series coil 9 and a shunt coil 8. The circuit of the generator 2 and battery 4 may be completed by the closing of the contacts 15 and 17; hence these contacts and the associated elements form a main circuit breaker, and it is to be noted that the series coil 9 is at the opposite end of the core 6 from the pole piece 7' adjacent to the armature 12, which controls the contacts 15 and 17. In circuit with the battery 4 are any desired translating devices such as incandescent electric lamps 32, electric horn 33, ignition coils 34, starting motor 35, etc., all connected in parallel across the supply mains.

The shunt coil 8 is connected in shunt across the terminals of the generator 2, the circuit being represented in Fig. 2 as extending from the upper terminal of the generator to the end plates and core of the magnet, thence through the shunt coil 8 to the other terminal of the generator. The shunt field winding 3 of the generator is also connected in shunt across the generator terminals with a resistance 36 in series therewith, the circuit extending from the upper generator terminal to the magnet end pieces and core, then through the resistance 36 and field winding 3 to the other generator terminal. At 37 there is shown a branch extending to the fixed contact 30, and from the intermediate point 38 of the resistance 36 there is another branch to the fixed contact 31. As shown in Fig. 2, all of the resistance 36 is short-circuited, the circuit through the field winding 3 being traced as follows: 37—30—25—23—7'—6—7. When the armature 22 is attracted by the pole-piece 7, the contacts 25, 30 open ahead of the contacts 26—31, so that the portion of the resistance coil 36 to the left of the point 38 is first cut in, and thereafter the whole of the resistance coil 36 is placed in series with the field coil 3. When the armature 22 is released from the pole-piece 7, the portion of the resistance 36

coil 36 to the right of the point 38 is first shunted and then the entire resistance coil 36 is shunted.

Around the core 6 between the two coils 8 and 9 is an iron collar or flange 40, the function of which will be pointed out later.

Directing attention particularly to the armature 12 and associated parts, it will be seen that when the pole-piece 7' attracts this armature 12, the contacts 15 and 17 are brought together. The continued movement of the armature 12 toward the pole-piece 7' brings the bridge 16 to strike the leaf spring 14, which carries the contact point 15 and 16 thus the contacts 15 and 17 are pressed firmly together. Between the time when the contact 15 initially touches the contact 17 and the time when the bridge 16 strikes the leaf spring 14, the intermediate movement of the armature 12 causes a slight transverse rubbing of the contact 15 on the contact 17 so that the meeting surfaces are kept bright. When the pole piece 7' releases the armature 12, the contact 15 slides in the reverse direction across the contact 17 until the part 12' of the armature 12 strikes the leaf spring 14, whereupon the contacts 15 and 17 are very suddenly separated as if by a hammer blow. The leaf spring 28 tends to rest 30 against the bridge 29 so that when the pole piece 7 attracts the armature 22, the bridge 29 strikes a hammer blow against the leaf spring 28, giving an abrupt separation of the contacts 26 and 31. There is the same 35 sliding action between the contacts 25, 30 and between the contacts 26, 31 as heretofore described between the contacts 15, 17.

Assuming that the generator 2 is being driven by the engine 1 at a speed such as 40 to cause the voltage generated thereby to approach or equal that of the storage battery 4, the current through the shunt or voltage winding 8 will be sufficient to cause the armature 12 to be attracted and thereby 45 close the contacts 15 and 17, and this will connect the charging generator through the series coil 9 to the circuit of the battery 4 and the translating devices 32, 33, 34 and 35. At the time of closing the charging circuit, the excitation of the controlling magnet 6 by the shunt coil 8 is not sufficient to attract the armature 22 and therefore the resistance 36 is short-circuited, giving a strong field excitation of the generator. 50 With this strong field, an increase of speed of the engine 1 gives a substantial increase in the charging current passing from the generator to the battery through the series coil 9. The magnetomotive force of this 60 coil 9 being additive to that of the voltage coil 8, the attraction of the armature 22 increases until it is drawn to the pole-piece 7 thus placing the resistance 36 in series with the field winding 3, in two successive steps 65 as heretofore indicated. The insertion of

this resistance 36 in series with the field winding 3 cuts down the field strength and thereby reduces the current output of the generator through the coil 9 so that its effect is insufficient to hold the armature 22 70 to the pole piece 7 against the force of the spring 18. Accordingly, the armature 22 falls back and cuts out the resistance 36 in two steps as already described and the field 75 3 strengthens and the flow of current 75 through the coil 9 again increases in consequence. Thereupon the same cycle of steps is repeated again and again in rapid succession. The armature 22 is given a vibratory movement which causes a fluctuating 80 current to flow from the dynamo armature.

The short-circuiting or cutting out of the resistance 36 causes the current in the series coil 9 to rise rapidly until the resistance controlling contacts 25, 30 and 26, 31 are separated. This is due to the proportion of the field winding 3 and resistance 36, and also due to the fact that the ohmic resistance in the circuit including the generator armature and the battery is extremely low, a comparatively small increase in the voltage of the generator making a large change in current through the battery 4 and series coil 9. But even a large change in the current through the battery 4 does not materially affect the 90 voltage across its terminals, because the internal resistance of the battery is so low that the increase of potential drop due to the current passing through the low battery resistance is very low compared with the normal counter volts of the battery, and the counter volts in the battery are substantially independent of the current through the battery. 95

It will be understood that the armature 12 105 serves as an automatic protective switch insuring that the generator will be connected in circuit with the battery only when the generator voltage is sufficiently high, and that if from any cause the generator voltage 110 becomes abnormally reduced the resultant reduction of current through the coil 9 not only will cause the pole-piece 7 to release the armature 22, but will cause the pole piece 7' to release the armature 12 and thereby break the charging circuit at the contacts 15, 17 with a quick hammer blow action in the manner heretofore described. The charging circuit through these contacts cannot again be closed until the voltage of the armature has risen sufficiently high. 115

For the sake of simplicity of construction and cheapness, it is an advantage to utilize one and the same core 6 to actuate both the circuit breaker with the contacts 15, 17 and 125 the vibratory armature 22. It is desirable to have the effect of the series coil 9 upon the vibrator 22 much greater than the effect of the shunt coil 8, so that a slight change in the current output of the generator will 130

make a material change in the attraction of the core 6 for the armature 22 in spite of the fact that the voltage is almost constant on account of the low internal resistance of 5 the storage battery 4. I have found that these advantages are attained and that it works very well to make the ampere turns of the series coil 9 about twice as much as for the shunt coil 8; this proportion gives a 10 good result in rapid and positive action of the vibrator 22. With these proportions, if the engine is standing, it will ordinarily have died down to that condition gradually enough so that the contacts 15, 17 will have 15 opened at an intermediate stage as heretofore described. But, if while the engine is standing, these contacts are pressed together by hand, or if they become closed in any other way, they will complete the low 20 resistance circuit through the battery 4 and generator armature 2 so that the battery current will flow in a reverse direction through the armature 2. Under these circumstances the ampere turns of the series 25 coil 9 will be opposed to those of the shunt coil 8, but the effect of the series coil 9 will so greatly exceed that of the shunt coil 8 that the coil 9 might have a tendency to hold the armature 12 and thus permit the battery 30 4 to run down, which would be bad enough even if the excessive current through the armature 2 did not burn the latter out.

By placing the iron collar or flange 40 between the series coil 9 and the shunt coil 8 35 upon the core 6, and by putting the series coil 9 at the opposite end of the core 6 from the armature 12 of the circuit breaker, this difficulty is obviated. With this arrangement, when the engine is standing still, even 40 if the contacts 15, 17, are closed manually, the resultant magnetic attraction by the end of the core 6 upon the armature 12 will not be sufficient to hold the contacts 15, 17, closed. As has already been stated, under 45 these circumstances the magneto motive forces produced in the core 6 by the two coils 9 and 8 will be opposite to each other; in so far as these magnetomotive forces are equal and opposite they will tend to form 50 substantially equal like poles at the ends of the core 6 and an intermediate opposite pole at the periphery of the flange 40. The increased magnetomotive force due to the greater number of ampere turns of the coil 55 9 creates an additional magnetomotive force which extends largely through the circuit indicated by the dotted lines 41 in Fig. 5 and in so far as this additional flux threading through the coil 9 emerges at the pole piece 60 7', it is not enough completely to overcome the opposing magnetomotive force of the shunt coil 8 and produce an effective attraction on the armature 12.

Accordingly, with the engine standing 65 still, if the contacts 15, 17 should be closed

manually or otherwise, thus permitting the battery current to flow in reversed direction through the series coil 9 and the generator armature 2, the resultant attraction of the core 6 on the armature 12 would be insufficient to hold the contacts 15, 17 closed in the absence of an abnormal and external force to hold them closed as just suggested.

Having thus described my invention, what I declare as new and desire to secure by 75 Letters Patent of the United States is:—

1. In combination, a direct current generator, a storage battery to be charged thereby, a permeable core with a collar of like character around it and with a series coil 80 and a shunt coil on respective sides of said collar, armatures at the respective ends of the core, a switch in series with the series coil controlled by the armature at the opposite end of the core from said series coil, 85 and means to regulate the field of the generator controlled by the armature at the end of the core opposite the shunt coil.

2. In combination, a direct current generator, a storage battery to be charged 90 thereby, and an electric regulator comprising a core with two coils thereon, armatures at the respective ends of the core, and means between the coils to facilitate the leakage 95 between the coils of a flux through one of said coils.

3. In combination, a direct current generator, a storage battery to be charged thereby, and an electric regulator comprising two coils on a common core, said core 100 having a branch of permeable material between the two coils, whereby a flux generated in the core by one coil may pass through said branch and complete its path without threading through the other part of the 105 core.

4. In combination, a direct current generator, a storage battery to be charged thereby, a series coil, a shunt coil, a common core 110 for said coils, a circuit breaker associated with the end of the core remote from the series coil, a regulator associated with the other end of said core, and means between the two coils to facilitate the leakage of magnetic flux from the core between said coils. 115

5. In combination, a direct current generator, a storage battery to be charged thereby, and an electric regulator comprising a core with two coils thereon, two armatures each pivoted near a respective end of the 120 core and each with a variable air gap near the other end thereof, two coils on said core and a branch path of permeable material between said coils, whereby a magnetic flux generated in the core by one coil can complete its circuit without threading through the other coil.

6. In combination, a direct current generator, a storage battery to be charged thereby, a series coil, a shunt coil, a common core 130

for said coils, two armatures each pivoted near a respective end of said core and with a variable air gap at the opposite end thereof, series contacts controlled by the armature 5 whose air gap is remote from the series coil and a branch path of permeable material on the core between the coils whereby a magnetic flux generated in the core by the series coil may complete its circuit without traversing the air gap for the armature that controls the series contacts.

7. In combination, a direct current generator, a storage battery to be charged thereby and a regulator, said regulator comprising two tandem coils on a common core, wound additively for production of flux under charging conditions, but oppositely under the condition of discharge from the battery through the generator, and means between 15 said coils to facilitate the leakage of flux at that point under such condition of discharge.

8. In combination, a direct current generator, a storage battery to be charged thereby and a regulator, said regulator comprising a series coil and a shunt coil in tandem 20 on a common core, the ampere turns of the

series coil being greater than of the shunt coil and both wound additively for production of flux under charging conditions, a cut-out 30 associated with the end of the core remote from said series coil and means between said coils to facilitate the leakage of flux at that point under conditions of opposite flux production thereby. 35

9. In combination, a direct current generator, a storage battery to be charged thereby and a regulator, said regulator comprising two coils on a common core wound additively for production of flux under charging conditions, but oppositely under the condition of discharge from the battery through the generator, a cut-out within the influence 40 of the magnetism additively produced in said core and means to facilitate leakage of flux from said core past said cut-out under conditions of opposite flux production by said coils.

In testimony whereof I affix my signature in presence of two witnesses. 50

WILLIAM SCHWAGERMANN.
